Attorney

UNITED STATES PATENT OFFICE.

THOMAS WHEWELL, OF NEW YORK, N. Y.

FOLDING FURNITURE.

Application filed February 13, 1923. Serial No. 618,881.

To all whom it may concern:

Be it known that I, THOMAS WHEWELL, a citizen of the United States, residing at New York, in the county of New York, 5 State of New York, have invented certain new and useful Improvements in Folding Furniture; and I do hereby declare the following to be a full, clear, and exact description of the invention, such as will enable 10 others skilled in the art to which it appertains to make and use the same.

This invention relates to new and useful improvements in folding furniture, and particularly to folding tables.

15 One object of the invention is to provide a device of this character which is simple in construction, formed of few parts, and which can be manufactured at a comparatively low cost.

20 Another object is to provide a device of this character which, when folded, will form a compact article, and which when unfolded or set up, will provide a rigid structure.

25 Other objects and advantages will be apparent when taken in connection with the accompanying drawings.

In the drawings:

Figure 1 is a side elevation of a table make in accordance with the present invention, the table being shown in set up position, partly broken away.

Figure 2 is an end view of the table in set up position.

Figure 3 is a bottom plan view of the table in set up position.

Figure 4 is a bottom plan view of the table in folded position.

Referring particularly to the accompanying drawings, 10 represents the top of the table, to the lower face of which are secured the transverse cleats 11 and 12, the former being disposed across the intermediate portion of the table top, while the latter are disposed adjacent the ends of the

40 top. Secured to the under face of the top, and depending therefrom, outwardly of the cleats, are the apron members 13 and 14, the former being disposed at the sides of the table top while the latter are disposed at the

45 ends thereof. Disposed within each corner angle formed by the meeting ends of the apron members is the upper end of a supporting leg 15, the outer portion of said upper end being cut away on a curved line,

50 as shown at 16, to permit the leg to swing on the hinge 17, by which it is connected to

the end cleat 12. Extending between the upper ends of each pair of legs 15 is a bracing and connecting strip 18, the upper portion of which is disposed inwardly of the 60 end apron member 14. Disposed transversely between each pair of legs is a rod 19, the ends of which are turned downwardly and secured to the inner faces of the legs by means of screws, or other suitable 65 fastening means. Rotatably embracing the rod 19, intermediate the ends thereof, is a clip or clamp 20, and disposed between the ends of the clamp, and secured thereto by means of the bolt 21, is the reduced end of 70 the bracing rod 22.

Secured to the lower face of the intermediate cleat 11 are the metal plates 23, each having a central transverse tubular portion 24 which receives the angularly 75 turned end 25 of the tubular rod 26, retaining collars 27 being disposed on the said end to maintain the end against longitudinal 80 slidable movement within the tubular portion. In the outer side of the angle of the 85 rod 26, and in line with the bore of the longer portion of the rod, is an opening 28 through which is adapted to project the end of the rod 22, which rod is telescoped into the rod 26. On the other end of the rod 26 is engaged an apertured cap 29, through which the rod 22 slides. On the tubular rod 26, adjacent the said cap 29, is a collar 30, and threaded through this collar and entering a recess in the rod 22, is a set screw 90 31, by means of which the rod 22 may be held against sliding movement through the rod 26, when the table is set up ready for use, and thereby permit the said rods 22 and 26 to perform their function as a brace 95 between the legs and the table top.

The opposite edge portions are grooved, as shown at 32, for the projecting ends of the rods 22 to slide therein, when the table is being folded and unfolded. It will be 100 understood that the set screw 31 is loosened when the table is being manipulated into and out of set up position, and then turned in tightly against the rod 22, to prevent any relative longitudinal movement of the rods 105 22 and 26.

While I have illustrated and described the invention as applied to tables, I wish it understood that it may be used with equal facility and effect, in connection with 110 benches, chairs, beds, or any similar piece of furniture, without departing from the spirit

2
of the invention or the scope of the appended claims.

What is claimed is:

1. A foldable piece of furniture including a top and legs pivotally connected to the ends thereof, hollow rods having angularly turned ends movably connected with the intermediate portion of the top, other rods pivotally connected with the legs and being 10 slidable through the hollow rods, the angular ends of the hollow rods being formed with openings at an angle to the movably connected portions thereof through which the other rods are arranged to slide, and 15 means for holding the rods against relative movement, at times.
2. A foldable piece of furniture including

a top and legs pivotally connected to the ends thereof, right-angular tubular members pivotally carried by the intermediate portion of 20 the top and having longer and shorter legs, the opening of the longer leg of each member extending through the angle of the member at right angles to the shorter leg, and an adjustable brace rod pivotally connected to each set of legs and slidable through said longer leg and beyond the shorter leg.

In testimony whereof, I affix my signature in the presence of two witnesses.

THOMAS WHEWELL.
